BUBBLE TURRET GUN TOY

Saul Robbins, 35 Mountain Way, West Orange, N.J., and
Isaac Heller, 2080 Arrowhead Drive, Scotch Plains,
N.J.

Filed Feb. 17, 1961, Ser. No. 63,975

Term of patent 14 years

(Cl. D34—15)

191,213. 2

FIG. 3

FIG. 4

FIG. 5

FIGURE 1 is a side elevation of a bubble turret gun toy showing our new design, the other side being a mirror image thereof;

FIGURE 2 is a top plan view thereof;

FIGURE 3 is a rear elevation thereof;

FIGURE 4 is a front elevation thereof; and

FIGURE 5 is a bottom view thereof.

We claim:

The ornamental design for a bubble turret gun toy, as shown and described.
